Application May 7, 1938, Serial No. 206,573

5 Claims. (Cl. 40—134)

This invention relates to improvements in sign or display devices and other illuminants, employing an ultraviolet exciting source.

An object of this invention is to provide in the 5 form of a simple device a luminescent light source energized by an ultraviolet light source.

The various detailed objects of this invention will be apparent from the following description of one form of the device when taken in connection 10 with the attached drawings.

This invention resides substantially in the combination, construction, arrangement and relative location of parts as set forth below.

In the accompanying drawings, 15 Figure 1 is a cross-sectional view on line 1—1 of Figure 2 of a device in accordance with this invention;

Figure 2 is a front elevational view thereof;

Figure 3 is a diagrammatic view, in perspective, of the plate elements forming the closure for the front of the device.

Figure 4 is a vertical, central, cross-sectional view of a modified form of device in accordance with this invention, illustrating it as adapted 25 particularly but not necessarily as a light source.

Figure 5 is a cross-sectional view taken on the line 5—5 of Figure 4.

In a broader sense, the invention is concerned with light sources including a display or sign 30 device by means of which house numbers, room numbers, doctors', dentists' and tourists signs and advertising displays may be produced employing as a primary source of energization a low wattage ultraviolet lamp. In front thereof 35 is placed a transparent or translucent screen having a luminescent coating thereon of any one of a large number of well known materials of this nature so as to be rendered luminescent under the excitation of the ultraviolet rays from the 40 light source.

In front of this plate is an opaque stencil plate having indicia to be displayed cut out of it, thereby exposing an area of the luminescent coating similar to the cut-outs. Placed over the 45 stencil to protect it, especially for outdoor use, is a transparent plate. The colors of the stencil and the coating, when luminescent under excitation, may be in complementary or contrasting colors to make the sign clearly visible at a 50 considerable distance and especially in the dark.

As shown in the drawings, the device may take the form of a box 1 of any suitable material such as metal, formed with side, end and bottom walls integral. The edges of the side and end walls 55 which define the open front may be formed, for

example, as shown at 2 to provide a reentrant flange having a seat 3 lying in a plane in back of the front edge. In the recess thus formed are placed plates which consist of a transparent or translucent plate 4, an opaque stencil plate 5, and a transparent cover plate 6. The plates 4 and 6 may be made of glass, Celluloid or other suitable materials, while the plate 5 may be made of metal, cardboard, "Bakelite" and similar materials.

On the rear face of the plate 4 is a coating 4a of any suitable material, of which there is a wide variety, which when excited by ultraviolet rays becomes luminescent. This coating may be applied in any suitable manner, as by brushing thereon, spraying or the like. The stencil plate 5 may have a cut-out of any desired outline, as for example an arrow, as indicated at 5a in Fig. 2. The three plates set in the recess formed by the reentrant flange against the seat 3 and are held in place by means of a suitably shaped frame 7 which fits on the end of the casing and is secured thereto in any suitable manner.

In back of the plates is a suitably shaped reflector 8. In the form illustrated in Figure 1, this reflector 8 is simply a strip of metal longitudinally curved, as shown, so as to have no top or bottom. As a modification, it is apparent that this reflector may be built into and become a part of the box 1. In other words, the box may be constructed so that the reflector is an integral part thereof. It is also within the purview of this invention to construct the reflector so that it is the box itself, thus simplifying the structure and reducing the cost thereof. Of course the reflector could be completed by providing reflecting top and bottom sides and it could be made in the form of a parabolic reflector or in any other suitable form. In back of the reflector is a socket of any suitable form to receive a small ultraviolet glow lamp 10, the stem of which projects through a properly placed opening in the reflector 8. This lamp has a pair of electrodes 11, in accordance with well known practice, which through the base of the lamp are connected to the circuit wires 12 and 13. When desired a variable resistance 14 may be included in the circuit to vary the intensity of the light source.

When the ultraviolet light source 10 is energized, the rays produced thereby are directed by the reflector 8 substantially uniformly over the rear surface of the plate 4 rendering the coating 4a thereof luminescent. That portion of the coating exposed by the stencil, when luminescent, will be clearly visible. The visibility of the ex-

posed portion of the coating may be somewhat increased by the color of the solid portion of the stencil. These two colors may be made to contrast so as to make the sign clearly visible. The 5 particular coating selected can be in part determined by the conditions under which the device will be used so that it is, for example, of a nature to be more readily visible in the daylight or in the dark, depending upon the intended use there- 10 of.

As illustrated in Figure 1, the portion of the bottom 1a of the box, and if desired the top, opposite the open sides of the reflector 8, could be made of transparent material such as glass, and 15 coated with a luminescent material as indicated by the stippling at 1b. Thus the coated area of the bottom of the box, when excited by the ultraviolet light 10, would itself become a source of light which would illuminate the area below 20 the device when in place. Thus, in the case of a house number sign, it could be so placed that in addition to displaying the house number, it would illuminate the steps for the safety and convenience of visitors.

25 In addition to the high visibility of a sign of this type at considerable distances, it has the advantage of being quite inexpensive to operate. This results mainly from the fact that coatings of this type require little energy for substantial 30 excitation, with the result that the ultraviolet light source may be so small as to require but for example one watt of power to operate it. Thus a sign of this type may be turned on and left burning day and night since its cost of opera- 35 tion is almost negligible.

A modified form of device, in accordance with this invention, is illustrated in Figures 4 and 5. In this form the device is more particularly adapted as a source of illumination of low intensity, 40 such as a night light, a sickroom light, and the like. It is shown comprising a suitably shaped transparent vessel 20 which, for example, can be made of glass. This vessel is shown as substantially circular in cross-section, with contracted 45 open ends. The upper end is closed by a plate 21 which may be secured to the vessel in any suitable manner, as for example by cement. Mounted on this plate is a suitable receptacle 23 in which is secured the ultraviolet light source 24, 50 similar to that previously described. Attached to the end plate 21, in any suitable manner, and surrounding the exciting lamp 24, is a reflector 22 of any suitable metal as before, such as for example aluminum or a chromium plated metal. 55 The lower contracted end of the vessel is closed by means of a cone-shaped reflector 26 arranged so that it will, in conjunction with the reflector 22, distribute the ultraviolet light from the source 24 substantially uniformly over the inner surface 60 of the vessel 20. The reflector 26 is provided with a flanged seat 27 by means of which it is secured to the vessel, as for example by cement. The exposed inner surface of the vessel 20 is coated with any one of a number of well known luminescent coatings, as indicated at 25, depending upon the color and other visible characteristics desired of the device as a light source. Such a light source will be exceedingly inexpensive to operate and at the same time will provide sufficient illumination for many purposes. The device can, of course, be easily adapted to display purposes by

the use of stencils, in conjunction with the coating 25, or by the use of several different coating materials applied in suitable designs.

As those skilled in the art will readily appreciate, the structural characteristics of these devices may be widely varied without departing from the novel subject matter thereof. Thus, for example, more than one side of the box may be provided with the plates 4, 5 and 6 when desired. In some cases, especially where the sign is to be used indoors, the plate 6 may be dispensed with and when it is to be used outdoors, special precautions can readily be taken to make the container watertight.

I do not, therefore, desire to be strictly limited 15 to the description as given for purposes of illustration, but rather to the scope of the appended claims.

What I seek to secure by United States Letters Patent is:

1. In a device of the type described the combination including a reflector, an ultraviolet light source in front thereof, a light transmitting plate in front of the reflector having a coating on the surface of said plate facing the light source 25 which is rendered luminescent by the light source, an opaque stencil mounted in front of said plate, and a transparent cover plate in front of said stencil.

2. In a device of the type described the combination including a container having an open front, a cover for said container including a transparent plate having a coating on the inner face thereof which becomes luminescent when excited by ultraviolet rays, and an opaque stencil superposed thereover, a reflector in said container and an ultraviolet light source between the reflector and said cover.

3. A sign of the type described comprising a box having an open side and formed at the opening with a seat, a plurality of plates held in said seat including a pair of light transmitting plates and an opaque stencil interposed therebetween, one of said plates having a coating thereon rendered luminescent under ultraviolet light excitation, and a source of ultraviolet light in said container.

4. A sign of the type described comprising a box having an open side and formed at the opening with a seat, a plurality of plates held in said seat including a pair of light transmitting plates and an opaque stencil interposed therebetween, one of said plates having a coating thereon rendered luminescent under ultraviolet light excitation, a source of ultraviolet light in said container and a reflector in said container for directing the rays from the source onto said coating.

5. A sign of the type described comprising a box having an open side and formed at the opening with a seat, a plurality of plates held in said seat including a pair of light transmitting plates and an opaque stencil interposed therebetween, one of said plates having a coating thereon rendered luminescent under ultraviolet light excitation, a source of ultraviolet light in said container, a reflector in said container for directing the rays from the source onto said coating, and circuit connections for said source including an adjustable resistance.
